UNITED STATES PATENT OFFICE.

THEODORE STIER, OF EAST LIVERPOOL, OHIO.

DESIGN FOR A SHAVING-MUG.

SPECIFICATION forming part of Design No. 12,599, dated December 13, 1881.

Application filed November 4, 1881. Term of patent 7 years.

To all whom it may concern:

Be it known that I, THEODORE STIER, of East Liverpool, in the county of Columbiana and State of Ohio, have invented and produced 5 a new and original Design for Shaving-Mugs, of which the following is a specification, reference being had to the accompanying drawings, forming part thereof, in which similar letters of reference indicate corresponding parts in 10 all the figures.

Figure 1 is a perspective view of my newly-designed shaving-mug. Fig. 2 is a perspective view of a modification of the same.

The mug A, which may have any suitable 15 size or shape, is provided with a handle, B, consisting of an imitation razor-handle, C, attached at its lower end to the lower part of the mug, the upper end of this imitation razor-handle C being united with a projection, D, 20 made in imitation of the lower end of a razor-blade, E, produced in relief or recessed, engraved, or painted on the side of the mug A.

The blade E may be represented as resting against the upper edge of the mug, as shown in Fig. 2, or the blade E may be represented 25 as extending downward at an inclination from the upper end of the imitation handle C.

Having thus fully described my invention, I claim as new and desire to secure by Letters Patent—

1. The design for shaving-mugs herein shown and described, the same consisting of an imitation razor-blade and handle on the mug, and forming the handle of the mug.

2. The design for shaving-mugs herein shown 35 and described, the same consisting of an imitation razor-blade, E, on the mug A, and an imitation razor-handle, C, forming the handle B of the mug.

THEODORE STIER.
